UNITED STATES PATENT OFFICE

1,969,165

EXERCISING DEVICE

Dee Turner, Hollywood, Calif.

Application May 17, 1933, Serial No. 671,508

4 Claims. (Cl. 272—79)

My invention relates to an exercising apparatus and has for its principal objects to generally improve upon and simplify the construction of existing forms of exercising devices and to provide a relatively simple, practical and inexpensive apparatus that may be conveniently used for exercising practically all muscles of the human body and particularly the muscles in the legs, arms, back and abdomen.

10 Further objects of my invention are, to provide an exercising apparatus that is comparatively light in weight and very compact so that it will occupy comparatively little space when packed for storage or transportation and further, to provide an exercising apparatus having an elastic element connected at its ends to hand and foot engaging members which when moved away from each other, stretches the elastic element so as to produce the desired results.

15 With the foregoing and other objects in view my invention consists in certain novel features of construction and arrangements of parts that will be hereinafter more fully described and claimed and illustrated in the accompanying drawing in which:

Fig. 1 is a side elevational view of an exercising device constructed in accordance with my invention.

Fig. 2 is an enlarged vertical section taken on the line 2—2 of Fig. 1.

Fig. 3 is a detail sectional view showing one end of the device anchored beneath a closed door.

Fig. 4 is an elevational view of the end of a strap that is utilized for connecting one end of the device to a stationary object such as the floor, wall or footrail of a bed or couch.

Fig. 5 is a top plan view of the bar that is carried by one end of the elastic element and which is adapted to be engaged by the hands of the user.

40 Fig. 6 is an elevational view of a modified form of the exercising device.

Fig. 7 is an elevational view of the parts seen looking in the direction indicated by the arrow 7 in Fig. 6.

45 Referring by numerals to the accompanying drawing and particularly to the form of device illustrated in Figs. 1 to 5 inclusive, 10 designates an elastic member preferably formed of rubber or in some instances an elongated coil of wire and 50 formed integral with both ends of this elastic member are rings or eyes 11.

Inserted through one of the rings 11, is a rod 12 of wood or light-weight metal and the projecting ends of this rod are adapted to be grasped by 55 the hands of the user of the device.

Inserted through the ring or eye 11 at the opposite end of the elastic element 10, is a rod 13 of wood or light-weight metal and which functions as a foot rest when the device is in use.

60 A flexible strap of leather or woven fabric has its central portion bent to form a U-shaped member 14, the parallel legs of which are positioned immediately adjacent to the sides of the ring or eye 11 that receives the footbar 13 and formed through the parallel legs of this U-shaped member are apertures 15 for the accommodation of rod 13.

65 Formed through each end of the strap are two or more apertures 16 that are adapted to receive the ends of rod 13 and by providing a plurality 70 of these apertures in each end of the strap the same may be adjusted for the accommodation of different sized feet.

75 The portions of the strap between the ends and the U-shaped intermediate portion 14 are of inverted U-shape so as to form loops 17 that pass over the instep portions of the feet of the user.

80 A flat flexible strap 18 of leather or woven fabric is positioned immediately above the rod 13, with the central portion of said strap resting on top of the ring or eye that receives the bar 13 and this strap 18 is provided with slots 19 for the accommodation of the strap that forms the foot receiving loops 17.

85 Strap 18 is considerably wider than the strap that forms the foot receiving loops 17 and said strap 18 provides a comfortable support for the feet when placed within said loops.

90 A strap 20 carries at one end a buckle 21 for the reception of the perforated opposite end of said strap and this strap extends between the lower portion of the ring or eye 11 that receives rod 13 and the lower portion of the U-shaped intermediate portion 14 of the strap that forms the foot receiving loops 17.

95 The doubled portions of strap 20 extend through slots that are formed in a disc 22 of leather or the like and which latter normally occupies a position adjacent to the buckle 21.

100 Loosely mounted on the lower portion of strap 20, between the disc 22 and buckle 21, is a snap hook 23 which when the device is in use is adapted to engage a screw eye 24 or the like and which latter may be inserted in the floor or in the base board of a wall.

105 In Fig. 1 the lower end of the exercising device is shown connected to a screw eye that is inserted in a base board and in Fig. 3 the lower end of the device is illustrated as anchored beneath a closed door.

When the device is anchored as illustrated in Fig. 3, the strap 20 passes between the lower edge of the closed door and the floor with the disc 22 bearing on said door and floor so as to prevent the strap from being pulled from its position beneath the door.

The lower end of the device may be secured to the foot rail of a bed, couch or the like or to the foot rail of the springs on a bed or couch by passing strap 20 around the foot rail and securing the free end of the strap to buckle 21 in the usual manner.

A person using the exercising device while standing on the floor, grasps the ends of the bar 12 in the hands and exerts pulling strains on the elastic member 10 so as to stretch the same and at the same time the user's body may be bent forwardly and backwardly simultaneously with the stretching and contraction of the elastic member, thereby exercising practically all muscles in the arms, back and abdomen.

The device may also be used by a person seated or lying on the floor, a bed or couch and when so used, the front portions of the feet are inserted through loops 17 with the soles of the feet resting on strap 18 and the ends of bar 12 are grasped in the hands. The user now pushes the feet forwardly and at the same time pulls rearwardly upon the handle bar 13, thereby stretching elastic member 10 and during these movements the torso may be swung rearwardly and downwardly and in so doing practically all of the muscles of the body, arms and legs are exercised.

35. The form of device illustrated in Figs. 6 and 7 is particularly designed for exercising the muscles in the legs, abdomen and back and this form of device comprises a foot engaging bar 25 and a strap or straps mounted on said bar to provide a pair of inverted U-shaped foot engaging loops 26.

A strap 27 similar to strap 20 and carrying a flexible disc 28, a buckle 29 and a snap hook 30 is secured to the central portion of the foot bar 25 and provides means for anchoring said foot bar and the loops 26 to the floor, beneath a closed door or to the foot rail of a bed or couch.

Where this form of device is used for exercising, the user inserts the forward portion of the feet through the loops 26 and while sitting or lying upon the floor, a bed or couch, the body is moved forwardly and rearwardly, thus exercising the muscles of the legs, abdomen and back.

55. The form of device illustrated in Figs. 8 and 9 is particularly designed for exercising the muscles in the legs, abdomen and back and this form of device comprises a foot engaging bar 35 and a strap or straps mounted on said bar to provide a pair of inverted U-shaped foot engaging loops 36.

A strap 37 similar to strap 20 and carrying a flexible disc 38, a buckle 39 and a snap hook 40 is secured to the central portion of the foot bar 35 and provides means for anchoring said foot bar and the loops 36 to the floor, beneath a closed door or to the foot rail of a bed or couch.

65. The form of device illustrated in Figs. 10 and 11 is particularly designed for exercising the muscles in the legs, abdomen and back and this form of device comprises a foot engaging bar 45 and a strap or straps mounted on said bar to provide a pair of inverted U-shaped foot engaging loops 46.

A strap 47 similar to strap 20 and carrying a flexible disc 48, a buckle 49 and a snap hook 50 is secured to the central portion of the foot bar 45 and provides means for anchoring said foot bar and the loops 46 to the floor, beneath a closed door or to the foot rail of a bed or couch.

Thus it will be seen that I have provided an exercising device that is relatively simple in construction, inexpensive of manufacture and very effective in performing the functions for which it is intended.

The entire device is very compact so that it may be packed into a comparatively small space for storage or transportation and the device in use is highly effective in exercising practically all muscles of the body, arms and legs.

It will be understood that minor changes in the size, form and construction of the various parts of my improved exercising device may be made and substituted for those herein shown and described without departing from the spirit of the invention, the scope of which is set forth in the appended claims.

I claim as my invention:

1. In an exercising device, an elastic member, a hand bar carried by one end of said elastic member, a foot bar carried by the opposite end of said elastic member, a foot engaging strap mounted upon said foot bar, means for securing the end of the elastic member that carries the foot bar to a fixed member and a foot supporting strap mounted on said foot engaging strap directly above said foot bar.

2. An exercising device, comprising an elastic member, a hand bar carried by one end of said elastic member, a foot bar carried by the opposite end of said elastic member, foot engaging loops carried by said foot bar, a strap connected to the end of the elastic member that carries the foot bar and a foot supporting strap mounted on said foot engaging loops immediately above said foot bar.

3. An exercising device, comprising an elastic member, a hand bar carried by one end of said elastic member, a foot bar carried by the opposite end of said elastic member, foot receiving straps carried by said foot bar, a strap connected to the end of the device that carries said foot bar and foot engaging straps, a flexible disc carried by said strap and a snap hook carried by said strap.

4. In an exercising device, an elastic member, a foot bar carried by one end thereof a strap detachably mounted on said foot bar and having inverted U-shaped portions that are adapted to receive the feet and a foot supporting strap carried by the looped portions of the first mentioned strap and positioned adjacent to said foot bar.
